US00D571025S

(12) **United States Design Patent**
Golden et al.

(10) **Patent No.:** US D571,025 S
(45) **Date of Patent:** ** Jun. 10, 2008

(54) **HEADLIGHT LENS**

(75) Inventors: **Edward R. Golden**, Pinckney, MI (US); **Philip Simmons**, Saffron Walden (GB); **Darrell P. Behmer**, Novi, MI (US); **Robert Todd Laster**, Wixom, MI (US); **Brad Richards**, Ann Arbor, MI (US); **Christopher Walter**, Walled Lake, MI (US); **Tobias France**, Detroit, MI (US); **Addam Ebel**, Dearborn, MI (US)

(73) Assignee: **Ford Global Technologies, LLC**, Dearborn, MI (US)

(**) Term: **14 Years**

(21) Appl. No.: **29/235,312**

(22) Filed: **Jul. 29, 2005**

(51) LOC (8) Cl. **26-06**

(52) U.S. Cl. **D26/28**

(58) Field of Classification Search D26/28-36;
362/459-468, 475-478, 485-487

See application file for complete search history.

(57) **CLAIM**

The ornamental design for a headlight lens, as shown and described.

DESCRIPTION

FIG. 1 is a frontal perspective view of a right headlight lens embodiment attached to a vehicle, no part of the vehicle is claimed;

FIG. 2 is a front side elevation view of the left headlight lens; FIG. 3 is a right side elevational view of the left headlight lens;

FIG. 4 is a left side elevational view of the left headlight lens;

FIG. 5 is a top plan view of the left headlight lens; FIG. 6 is a bottom plan view of the left headlight lens embodiment;

FIG. 7 is a frontal perspective view of an alternative embodiment of the headlight illustrated in FIGS. 1-7, showing a right headlight lens attached to a vehicle, no part of the vehicle is claimed;

FIG. 8 is a front side elevation view of the right headlight lens;

FIG. 9 is a left side elevational view of the right headlight lens;

FIG. 10 is a right side elevational view of the right headlight lens;

FIG. 11 is a top plan view of the right headlight lens; and, FIG. 12 is a bottom plan view of the right headlight lens. The phantom lines are not a part of the claimed invention.

1 Claim, 12 Drawing Sheets
